(57) **CLAIM**

The ornamental design for a bottle for olive oil, as shown and described.

DESCRIPTION

FIG. 1 is a top, side and front perspective view of a bottle for olive oil showing the new design;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof, the orientation being relative to the bottle for olive oil shown in FIG. 2.
